UNITED STATES PATENT OFFICE.

IRA T. LEAGER, OF RIDGELY, MARYLAND.

COMMUTATOR.

1,371,697.

Specification of Letters Patent. Patented Mar. 15, 1921.

Application filed April 28, 1919, Serial No. 293,217. Renewed September 24, 1920. Serial No. 412,614.

To all whom it may concern:

Be it known that I, IRA T. LEAGER, citizen of the United States, residing at Ridgely, in the county of Caroline and State of Maryland, have invented certain new and useful Improvements in Commutators, of which the following is a specification.

This invention relates to an improved commutator for internal combustion engines and 10 more particularly to a commutator for engines of the Ford type, the invention having as one of its principal objects to provide a device of this character wherein the circuit wires leading to the commutator as well 15 as the connections between the circuit wires and the contacts of the commutator will be prevented from becoming oil soaked and covered with grease and dirt.

A further object of the invention is to 20 provide a commutator wherein the connections between the circuit wires and the contacts of the commutator will all be housed within the commutator cap but wherein the cap may be easily removed so as to permit 25 access to said connections.

And the invention has as a still further object to provide an improved type of commutator contact.

Other and incidental objects will appear 30 hereinafter. In the drawings:

Figure 1 is a fragmentary side elevation showing my improved commutator in position upon an engine of the Ford type.

Fig. 2 is a fragmentary vertical sectional 35 view taken centrally through the device,

Fig. 3 is a fragmentary perspective view showing a portion of the commutator shell and insulating plate,

Fig. 4 is a detail perspective view showing 40 the type of commutator contact employed, and

Fig. 5 is a perspective view showing a slightly modified form of contact.

Referring now more particularly to the 45 drawings, I have shown my improved commutator in connection with an engine 10 of the Ford type. This engine is provided with the usual timing gear case 11 which is formed in its forward side with an opening 50 surrounded by an annular flange 12. Projecting through the timing gear case is the forward end of the cam shaft 13 of the engine. Coming now more particularly to the subject of the present invention, I employ 55 an annular commutator shell or body 14. This shell removably fits within the flange

12 and fixed within the shell at its outer end is a plate 15 of insulating material secured by a plurality of radially disposed screws or other suitable fastening devices 16 60 engaged through the shell and threaded into the peripheral margin of the plate. The plate may be formed of fiber or other approved insulation and is provided centrally with an opening 17 surrounding the forward 65 end of the cam shaft 13. Mounted upon this plate and insulated with respect to each other thereby is a plurality of contacts 18, being four in number to correspond to the number of cylinders of the engine. One 70 of these contacts is shown in detail in Fig. 4 and, as there illustrated, the contacts each comprise an arcuate contact plate preferably struck on an arc concentric to the axis of the shaft 13 and provided at one end with 75 a reduced portion which is bent laterally at substantially right angles to define a forked or slotted contact post 19. The plates of the contacts are, as particularly illustrated in Fig. 2, countersunk in the inner side face of 80 the plate 15 while the binding posts 19 extend through the plate so that the forked outer ends thereof project into recesses 20 in the front face of the plate, the binding posts serving to rigidly secure the contacts upon 85 the plate. In this connection it will, of course, be understood that the contacts are arranged in concentric relation to the shaft 13 and at equally spaced points about the insulating plate. At its periphery, the insulating plate is cut away for a portion of 90 its width to define an annular channel and snugly fitting within the commutator shell to engage at its inner end within this channel is a cap 21. As will be seen, this construction provides an arrangement whereby in practical use, water which may beat in 95 against the commutator will first be directed by the flange 12 of the timing gear case onto the commutator shell when the shell will, 100 since said shell overhangs the margin of the cap at its inner end, direct the water onto the exterior surface of the cap so that the water will be effectually prevented from finding its way into the commutator to cause 105 trouble. The cap is substantially frustoconical in general contour and at its apex is formed with a socket 22 in which is engaged the free end of the usual spring arm 23 commonly found upon the Ford type of 110 motor, this arm acting to removably hold the cap engaged with the commutator shell.

Extending radially from the cap at one side thereof and adjacent its inner end, is an arm 24 to which is connected in the usual manner, the customary pull rod operable for 5 rotating the commutator to advance or retard the time of firing of the engine cylinders. Embedded in the plate 15 at opposite sides thereof are, as particularly shown in Fig. 3, pins 25. At its inner end, the cap 10 is slotted to freely receive these pins and, as will be observed, the pins are staggered with respect to each other so that the cap can be fitted upon the shell only in proper position with respect thereto.

15 Mounted upon the forward end of the cam shaft 13 is an arm 26 provided at its inner end with a sleeve 27 fixed to the shaft by a cotter pin 28 engaged in opposite notches in the forward end of the sleeve. 20 At its outer end the arm is formed with a socket 29 in which is freely engaged a spring pressed contact brush 30 adapted to coöperate with the contacts 18. Fitting over the outer end of the shaft 13 is a cap 31 overlying the forward margin of the sleeve 27 and threaded upon said shaft is a nut 32 binding the cap in position.

Leading into the cap 21 of the commutator is a metal sheathed cable 33. At its forward 30 end this cable is fitted through a suitable opening in the lower side of the cap and is thus fixed to the cap. The cable carries the circuit wires 34 leading to the commutator. At their adjacent ends these wires are inserted in the slots in the outer ends of the binding posts 19 when the forks of said posts are bent about the wires to firmly impinge thereagainst and securely connect the wires with the posts. As will be appreciated, I thus provide a very advantageous type of contact since the contact and its binding post may be readily formed from a single piece of material while provision is made for effectively connecting, without the 40 use of separate fastening devices, a circuit wire with the binding post. Furthermore, by employing a contact of such type, the insulating plate 15 may be of minimum thickness so that the device may accordingly be produced at proportionately reduced cost.

Particular attention is now directed to the fact that the circuit wires 34 leading to the commutator will be protected by the cable 33 while the forward free ends of said wires 50 as well as the connections between the wires and the contacts of the commutator will be protected by the commutator cap 21. Consequently the wires will be prevented from getting oil soaked and will be protected from 60 grease and dirt. The superior advantages of this structure will be readily appreciated. Should it be desired to gain access to the binding posts 19 of the commutator contacts, the commutator cap may simply be detached 65 from the commutator shell. On the other

hand, should it be desired to gain access to the contact plates, this object may be accomplished by simply removing the commutator shell from within the flange 12 of the timing gear case when access may also be readily had to the brush 30 and associated parts.

In Fig. 5 of the drawings, I have illustrated a slightly modified form of commutator contact. In this modification the contact is, like the preferred construction, preferably formed from a single strip of suitable resilient sheet metal. The metal strip is first bent intermediate of its ends to provide a contact plate 35 formed by overlapping the strip upon itself when the 80 end portions of the strip are bent to project laterally from the plate at a point substantially midway of the ends thereof, mating to define a hollow binding post 36, the end portions of the strip being 85 transversely curved so that the binding post is cylindrical. This binding post is internally screw threaded to receive a binding screw 37 so that a circuit wire may, as will be readily understood, be easily connected 90 with the contact by said screw. As will be seen, this modified form of contact thus provides a very simple construction and it is believed, in view of the preceding description, that the manner in which the modified type 95 of contact is mounted upon the insulating plate of the commutator will be readily understood.

Having thus described the invention, what is claimed as new is:

1. A commutator including a shell, an insulating plate therein provided at its periphery with a groove, a contact mounted upon said plate, and a cap fitting at its inner end within the shell and engaging in said 105 groove.

2. A commutator including a shell, an insulating plate therein, and a contact mounted upon the insulating plate and including a contact plate having one end portion thereof bent to provide a binding post engaging through the insulating plate and supporting the contact thereon, the opposite end portion of the contact plate lying at the inner side of the insulating plate to provide a contact 115 surface.

3. A commutator including a shell, an insulating plate therein, and a contact carried by said insulating plate and including a contact plate provided at one end with a forked 120 binding post engaged with the insulating plate and supporting the contact thereon, the forks of said post being engageable with a circuit wire for connecting the wire with the post.

4. A commutator including a shell, an insulating plate therein, and a contact mounted upon the plate and including a contact plate bent to provide a laterally directed slotted binding post, the binding post being 125 130

engaged with the insulating plate for supporting the contact thereon and the slot in said post being adapted to receive a circuit wire whereby the wire may be connected to the post.

5. A commutator including a shell, an insulating plate therein, a contact carried by said plate, and a cap telescoping at its inner

end portion within the outer end portion of the shell whereby the shell will overhang the 10 cap at the joint therebetween for directing moisture away from said joint exteriorly of the cap and shell.

In testimony whereof I affix my signature.

IRA T. LEAGER. [L. S.]
